US0D1067373S

(12) **United States Design Patent** (10) **Patent No.:** **US D1,067,373 S**
Xin (45) **Date of Patent:** **** Mar. 18, 2025**

(54) **POND FISH POND WATER TREATMENT FILTER**

(71) Applicant: **Shenzhen Longchengxingqi Technology Co., Ltd.**, Shenzhen (CN)

(72) Inventor: **Peng Xin**, Shenzhen (CN)

(*) Notice: Patent file contains an affidavit/declaration under 37 CFR 1.130(b).

(**) Term: **15 Years**

(21) Appl. No.: **29/957,206**

(22) Filed: **Aug. 12, 2024**

(51) LOC (15) Cl. **23-01**

(52) U.S. Cl.

USPC **D23/207**

(57) **CLAIM**

The ornamental design for a pond fish pond water treatment filter as shown and described.

DESCRIPTION

FIG. 1 is a perspective view of a pond fish pond water treatment filter showing my new design;
 FIG. 2 is another perspective view thereof;
 FIG. 3 is another perspective view thereof;
 FIG. 4 is a front view thereof;
 FIG. 5 is a back view thereof;
 FIG. 6 is a left view thereof;
 FIG. 7 is a right view thereof;
 FIG. 8 is a top plan view thereof; and,
 FIG. 9 is a partial enlarged view of portion 9 in FIG. 8. The broken lines depict portions of the pond fish pond water treatment filter and form no part of the claimed design.

1 Claim, 9 Drawing Sheets
